UNITED STATES PATENT OFFICE.

HENRI GALLET, OF PUTEAUX, FRANCE, ASSIGNOR TO ETABLISSEMENTS DE DION BOUTON, SOCIÉTÉ ANONYME, OF PUTEAUX, FRANCE, A CORPORATION OF FRANCE.

PLUG CONTACT-MAKER.

1,240,965.

Specification of Letters Patent. Patented Sept. 25, 1917.

Application filed December 26, 1916. Serial No. 138,949.

To all whom it may concern:

Be it known that I, HENRI GALLET, a citizen of the Republic of France, residing at #36 Quai National, at Puteaux, Department of the Seine, France, have invented certain new and useful Improvements in Plug Contact-Makers; and I do hereby declare the following to be a full, clear, and exact description of the invention, such as 10 will enable others skilled in the art to which it appertains to make and use the same.

Plug contact-makers with contact studs grouped at their upper part and intended for the electrical ignition of explosion motors now in use exhibit the disadvantage of necessitating internal connections of considerable length, thus increasing the difficulties of casting and insulation.

The present invention relates to a contact 20 make and break device or distributor that enables the length of a part of the internal connections to be considerably reduced by employing a rotary brush carrier comprising two or more brushes electrically connected and arranged at suitable angles apart. These brushes establish in succession appropriate connections with two or more series 25 of contact studs arranged in a suitable manner in the upper part of the distributor.

30 The accompanying drawing shows by way of example a constructional form in accordance with this invention, intended for the ignition of an eight-cylinder explosion motor.

35 Figure 1 is a section through the longitudinal axis of the contact maker and of the rotary brush carrier.

Fig. 2 is an end view.

In Fig. 1, *a* represents the fixed casing of 40 the contact maker, made of special insulating material in which a cylindrical hollow *b* is formed. The internal peripheral surface of the casing is provided with two sets of contact studs, imbedded in the insulating 45 material, located in two different planes *c* and *d*, and distributed regularly over the upper half inner portion of the cylindrical casing *b*.

Fig. 2 shows that the projection of the 50 four contact studs of the first row *c* on a plane normal to the axis of the contact

maker is merged in the projection of the other four contact studs, of the second row *d*.

Under these circumstances the two brushes *f* and *f'* are successively engaged on the contact studs corresponding to them, the first half of the ignition cycle being traversed by the brush *f* and the second half by the brush *f'*.

The device forming the subject matter 60 of the present invention may be advantageously extended to all multi-cylinder motors, if the number of cylinders is equal to or greater than four.

Of course a smaller number of contact 65 studs may be made use of in each set and a larger number of sets, and of brushes displaced from one another through a suitable angle, so as to obtain regularly timed ignition in the various cylinders.

Having now particularly described and ascertained the nature of my said invention and in what manner the same is to be performed, I declare that what I claim is:—

1. A contact make and break device comprising a hollow casing, a plurality of contact studs disposed in the upper part of the casing in sets, the members of each set being spaced apart predetermined distances, a rotary member in said casing having at least 75 two brushes electrically connected together and adapted, upon the movement of the rotary member, to successively engage said contact studs.

2. A contact make and break device comprising a hollow casing, a plurality of contact studs disposed in the upper part of the casing in sets, the members of each set being spaced apart predetermined distances, a rotary member in said casing having brushes 85 arranged on the same in such manner that during the movement of the rotary member one brush will successively engage the members of one set of contacts and another brush will subsequently successively engage the 90 members of another set of contacts.

In testimony whereof I affix my signature in presence of two witnesses.

HENRI GALLET.

Witnesses:

CHAS. P. PRESSLY,
HENRI COHEN.
